UNITED STATES PATENT OFFICE

155,606

DESIGN FOR A TOY AUTOMOBILE

John O. Heinze, Bessemer, Ala.

Application December 26, 1946, Serial No. 135,758

Term of patent 3½ years

(Cl. D34—15)

To all whom it may concern:

Be it known that I, John O. Heinze, a citizen of the United States, residing at Bessemer, in the county of Jefferson and State of Alabama, have invented a new, original, and ornamental Design for a Toy Automobile, of which the following is a specification, reference being had to the accompanying drawing, forming a part thereof.

In the drawing:

Fig. 1 is a side elevational view of a toy automobile showing my new design;

Fig. 2 is a front elevational view thereof; and,
Fig. 3 is a top plan view thereof.

I claim:

The ornamental design for a toy automobile, substantially as shown.

JOHN O. HEINZE.
